UNITED STATES PATENT OFFICE.

CHRISTIAN G. LASSEN, OF NEW YORK, N. Y., ASSIGNOR TO SHUR LOC ELEVATOR SAFETY CO., INC., OF NEW YORK, N. Y., A CORPORATION OF NEW YORK.

ELEVATOR.

Application filed February 23, 1922. Serial No. 538,525.

To all whom it may concern:

Be it known that I, CHRISTIAN G. LASSEN, a citizen of Germany (who has declared his intention to become a citizen of the United States), residing at 219 West 127th Street, in the borough of Manhattan of the city of New York, in the State of New York, have invented certain new and useful Improvements in Elevators, of which the following is a specification, reference being had to the accompanying drawings, forming a part hereof.

This invention relates particularly to the operation of the car doors and of the shaft doors of elevators and has for its general object to provide power actuated means for the operation of such doors under the control of the operator, whereby the doors shall be opened and closed with less delay in the operation of the elevator than when the doors are opened and closed by the operator, suitable provisions being made for the interlocking of the door controlling and operating devices with the elevator controlling mechanism so as to guard against accidents. In the embodiment of the invention chosen for illustration and explanation of its nature, there is placed in the elevator car, in convenient proximity to the car controlling lever, a door controlling handle by the manipulation of which the car door and the shaft door opposite which the car is stopped are coupled operatively with a source of power, the source of power for the operation of the doors being preferably a power storage device in which power is stored by the movement of the car in the shaft. Such power storage device may comprise most conveniently a weight which is carried with the car but is movable with respect to the car, means being provided whereby the weight is raised, with reference to the car, by the movement of the car in either direction, is retained in its highest position until its action is required for the opening or the closing of the door or doors and is released under the control of the operator for the purpose of opening or of closing the door or doors as the case may be. In the particular construction shown and described herein as a preferred embodiment of the invention, a cable, made fast at its upper and lower ends at the top and the bottom of the elevator shaft, is passed in an S-loop about

suitable guides carried by the car, so that when the car is moving downwards a weight mounted movably on the car shall be raised, with respect to the car, if connected at that time to one member of the S-loop of the cable, and shall also be moved upward, with respect to the car, if connected to another member of the S-loop of the cable, when the car is moving upward. As a matter of fact any selected point in either of the two standing parts or outer members of the looped cable has no vertical movement in space so that the weight, connected to one of such parts during the downward movement of the car, is raised with respect to the car, while any point in the intermediate portion of the looped cable, that is the portion between the two guides on the car, has an upward movement in space at a speed twice that of the upwardly moving car, so that if the weight is connected to such intermediate portion of the cable when the car is moving upward the weight will be raised with respect to the car. When the weight stands in its highest position with respect to the car it is released from the power storing or weight lifting cable and thereafter continues to move with the car until the stored power or weight is to be applied to the door or doors, being held in its power storing or elevated position by devices carried by the car. When, however, movement is to be imparted to the door or doors, the power storing device or weight is released from the holding means and, being at that time free from the power storing or lifting cable, falls in space and with respect to the car, which is then stationary, and, being then operatively connected with the door or doors, opens or closes the same as may be required. The invention is concerned mainly with the means for effecting the several operations just referred to, but is concerned also with the device whereby each shaft door, opposite which the car is brought to rest, is opened or closed with the car door. The invention will be explained more fully hereinafter with reference to the accompanying drawings in which it is illustrated and in which—

Figure 1 is a view in elevation, broken out to save space, of an elevator car which is equipped with devices adapted for the practice of the invention.

Figure 2 is a partial view of the same in elevation as seen from the left hand in Figure 1.

Figures 3, 4 and 5 are detail views, on a 5 large scale, illustrating particularly certain interlocking connections to prevent movement of the car when the doors are in any other than the closed position.

Figures 6, 7 and 8 are detail views on a 10 still larger scale illustrating particularly the power storage device or weight and the means for coupling and uncoupling the same to and from the fixed power storing cable, the holding means and the power transmitting means, Figure 7 being a view in section on the plane indicated by the broken line 7-7 of Figure 6 and Figure 8 being a top view of the parts shown in Figure 6.

Figures 9, 10 and 11 are detail views illustrating 15 particularly the devices for effecting operative engagement between the shaft door and the door operating device, Figure 10 being a view in vertical section on the plane indicated by the broken line 10-10 20 of Figure 9, and Figure 11 being a view in horizontal section on the plane indicated by the broken line 11-11 of Figure 9.

Figures 12, 13 and 14 are diagrammatic views which illustrate respectively the positions of the several clutch controlling cams when the door controlling handle is in neutral position, is in position for opening the doors, and is in position for closing the doors.

In the drawings, Figures 1 and 2, there is shown at a a portion of the frame of an ordinary elevator car, the floor of which is indicated at a' . The car may be raised and lowered in the elevator shaft by any 40 suitable means. It may have a door, indicated at a^2 , and may be provided with a controller box a^3 having a controller handle a^4 and with an interlocking rod a^5 which operates in the usual manner to prevent 45 the movement of the controller handle to start the car when the car door or the shaft door, as hereinafter described, is not in closed position. At each shaft landing there is a door of any desired construction, 50 indicated in part at b in Figure 9.

A cable c , referred to herein as the power cable or lifting cable, is fixed at its upper and lower ends at the top and bottom of the elevator shaft and is passed in an S- 55 loop over guide pulleys c' , c^2 and c^3 which are mounted on the car, one of the members as c^4 of the loop serving to effect, as hereinafter described, a movement of the power storage device or weight in one direction with relation to the car during the 60 downward movement of the car and the other member of the loop, as c^5 , serving to effect a relative movement of the power storage device or weight in the same direction with respect to the car when the 65

car is moving upward. In this manner the movement of the elevator car in the shaft is made to store power for the operation of the car door and of the shaft doors, whether the car be moving up or down. 70

The power storage device may be of any suitable character, but is preferably a weight d , which may be made up of the required number of sections, arranged to slide vertically with respect to the car on 75 suitable vertical guides a^6 . In a suitable frame d' to which the power storage device or weight d is secured are arranged clutch devices or coupling devices adapted to effect engagement of the power storage device 80 or weight, at the will of the car operator, with the power storage cable c hereinbefore referred to, with holding rods e which at their upper and lower ends are secured to the car, and with the members of the looped 85 transmitting cable f . The weight d and the frame d' are suitably channeled to receive the power storage cable, the holding rods and the members of the looped transmission cable. 90

Each clutch or coupling device, marked respectively g' , g^2 , g^3 , g^4 , g^5 and g^6 , in the construction shown, comprises a yoke g^7 arranged to move vertically in the frame d' and provided with a vertical guide stem g^8 , 95 and a clutch roller g^9 , the shaft g^{10} of which is received in inclined slots g^{11} of the yoke g^7 . The frame d' is formed interiorly with a cam surface d^2 , so that when the yoke g^7 moves upwardly in the frame the cam 100 surface d^2 co-operates with the roller g^9 to force the same toward the plate d^3 of the frame d' and thereby to clamp the corresponding cable or rod between the roller and the frame and so clutch or couple the 105 power storage device or weight to the corresponding cable or rod. When the yoke g^7 moves down within the frame d' the roller g^9 is permitted to move away from the plate d^3 of the frame and the power 110 storage device or weight is thereby disconnected from the corresponding cable or rod. Each yoke g^7 is lifted into operative position by a spring g^{12} , to effect the clamping 115 action described, and is depressed, in order to release the rod or cable, by devices about to be described.

In pedestals d^4 erected on the frame d' and therefore carried with weight d , is mounted for rotation a cam shaft h which is armed with cams h' , h^2 , h^3 , h^4 , h^5 , and h^6 for co-operation respectively with the clutch member g' , g^2 , g^3 , g^4 , g^5 and g^6 , each cam acting through a roller h^7 and a slotted presser h^8 which is connected through an adjusting 125 screw h^9 with the vertical guide stem g^8 of the corresponding clutch yoke g^7 , the spring g^{12} , which lifts the yoke, being interposed between the top of the frame d' and the foot of the presser h^8 . The cam shaft is oscillated 130

in one direction or the other to effect the disengagement of the clutches at the proper time, by the car operator. In the embodiment of the invention shown the shaft h 5 has at one end a bevel gear h^{10} which is in mesh with the bevel gear h^{11} , supported by the bracket d^4 so that it moves with the weight and with the car, and has a key h^{12} which engages a keyway h^{13} formed in a vertical shaft h^{14} . The latter is mounted, at its 10 upper and lower ends, in suitable bearings carried by the car, and at its upper end is connected by suitable linkage, h^{15} , with an operating shaft h^{16} which is provided with 15 an operating handle h^{17} in convenient proximity to the controller handle a^4 .

In the arrangement of the clutches and cams shown, the clutches g' and g^6 co-operate respectively with the holding rods e or their 20 equivalents, of which two are preferably provided, although each one serves the necessary purpose. The clutches g^2 and g^5 co-operate respectively with the members c^5 and c^4 of the looped, power storage or weight 25 lifting cable c , while the clutches g^3 and g^4 co-operate respectively with the members f' and f^2 of the looped transmission cable f to be referred to hereinafter.

In order that the power storage or weight 30 lifting cable may be disconnected from the power storage device or weight when the required power has been fully stored, that is, when the weight has reached its highest position with respect to the car, without requiring any action on the part of the operator, each of the pressures h^8 , of the clutches g^2 and g^5 , is provided with an upward extension h^{8x} so that, as the weight approaches 35 its highest position with respect to the car, such extensions shall contact with a bar i supported yieldingly near the top of the car by rods i' preferably provided each with a resistance spring i^2 and a dashpot i^3 , and shall be depressed thereby (with respect to 40 the cam shaft and clutches), and so release the power storage or lifting cable from the weight, which is held in its elevated position by the automatic engagement of the clutches g' and g^6 with the holding rods e . It will be 45 understood that as the lifting of the weight to its highest position may be accomplished either during upward movement of the car or during downward movement of the car, the automatic disengagement of the weight, 50 when it reaches its highest position, must be effected from whichever member of the looped cable may be in engagement with the weight at the time, and that both clutches g^2 and g^5 must therefore be open.

The transmitting cable f is looped at its lower end around a driving pulley f^8 , supported below the floor a' of the car and to be referred to again hereinafter, while the two 55 portions f' and f^2 of the cable, being passed over guide pulleys or idlers f^4 near the top

of the car, are wound in opposite directions about and are secured to a drum k which is mounted in suitable bearings on the car near its top. On the shaft of the drum k is fixed a sprocket wheel k' and mounted on 70 suitable bearings at the other side of the car is an idler sprocket wheel k^2 . The two ends of a chain k^3 , which is passed about the sprocket wheels k' and k^2 , are connected to a traveller k^4 which is mounted in suitable 75 guides k^5 to move horizontally across the car and is connected, as by an arm k^6 , with the car door a^2 . It will now be seen that when the weight d is disconnected from the holding rods e and descends, with respect to the 80 car, and is coupled through one or the other of the clutches g^3 , g^4 , with one member or the other of the looped transmission cable f , through movement of the cam shaft h at the will of the operator, the traveller k^4 will be 85 moved in one direction or the other across the car through the expenditure of the energy which had been stored in the power storage device or weight, and that the car door a^2 will be moved to open or to closed 90 position as the case may be, such movement being continued until the traveller is brought to rest by the stops which limit its movement or until the operator moves the handle h^{17} to neutral position and thereby uncouples 95 the weight from the transmission cable and permits it to be engaged with the holding rods or with the power storage cable as the case may be.

The pulley f^3 , above mentioned, is rotated 100 in one direction or the other by the movement of the transmission cable f and this movement, when the car door is being opened, is made use of to lock the car controller through movement of the usual locking rod 105 a^5 . As shown the pulley f^3 is fixed on a shaft f^5 which is mounted in suitable bearings below the floor of the car and is armed with a screw thread as at f^6 . The threaded portion f^6 of the shaft f^5 is engaged by a 110 traveling nut f^7 which carries an arm f^8 . The free end of the latter when moved by an opening of the door, contacts with one arm of a bell crank lever f^9 , which has a horizontal arm f^{10} . A link f^{11} , connected to the arm f^{10} , slotted longitudinally at its upper end, engages one arm of a three-armed lever a^7 , which is connected with the slotted lower end of the locking rod a^5 . Movement of the nut f^7 , when the car door 115 is being opened, will therefore cause the locking rod a^5 to be moved into locking position, so that the controller handle a^4 is locked against the movement to start the car when the car door has been started from its 120 closed position.

As a further safety locking device, to prevent the movement of the controller to starting position when the door is being moved in either direction, the shaft h^{14} , which is 130

moved from its neutral position in one direction or the other by the movement of the door controlling handle h^{17} , is provided near its lower end with a transverse pin h^{13x} , the 5 ends of which are engaged by the two slotted members of a forked link a^8 , which is connected with the vertical arm of the three-armed lever a^7 , so that any movement of the shaft h^{14} in either direction from its neutral 10 position, for the purpose of bringing about movement of the car door will effect the movement of the locking rod a^5 to position to prevent starting movement of the car controlling handle a^4 . The slotting of the lower 15 end of the locking rod a^5 , of the upper end of the link f^{11} , and of the two members of the forked link a^8 , permits movement of the locking rod a^5 under the influence of either of the safety devices just described 20 or in the operation of the usual emergency release indicated at a^9 in Fig. 1.

The movement of the car door a^2 is made to effect corresponding movement of the shaft door opposite which the car is brought 25 to rest. This has been accomplished heretofore by providing upon the car door or upon the traveller by which it is moved, a pair of fixed, vertical shoes, spaced apart and adapted to receive between them a stud fixed 30 to or connected to the shaft door so that movement of the car door shall effect movement of the shaft door. It has been found in practice that the fixed shoes require careful adjustment and even then are a source 35 of trouble through unintended contact with portions of the elevator shaft or its equipment during the movement of the car. In the present case the shoes which move with the car door and effect the movement of the 40 shaft door, are movably mounted so that they may stand normally out of operative position and therefore out of position for unintended contact with parts of the elevator shaft and its equipment and may be 45 moved into operative position only when the car operator moves the door controlling handle h^{17} to bring about the opening or the closing of the door. In the arrangement 50 shown two shoes m , suitably shaped, as shown in Figures 1, 9, 10 and 11, are pivotally hung, as at m' , so as to swing upon vertical axes, from the inoperative position indicated by broken lines in Figure 11 to the operative position indicated by full lines 55 in the same figure, the two shoes being spaced apart, when in operative position, so as to receive between them the coacting device on the shaft door. The arms m^2 , both upper and lower, which carry the vertical 60 portions of the shoes m are provided with intermeshing gears m^3 , so that the two shoes shall move together but in opposite directions. The arms are also provided with 65 contacting faces m^4 for co-operation with an actuating member m^5 which is secured to

a vertical shaft m^6 supported in suitable bearings carried by the guide rails k^5 and located in line with the middle of the space between the shoes m when the car door is closed. The shaft m^6 is operatively connected with the operating shaft h^{16} , so that the actuators m^5 shall be swung from their normal or neutral position, indicated by the broken line in Figure 11, to one side or the other, as indicated by full lines in Figure 75 11, when the door controlling handle h^{17} is moved to one side or the other from its neutral position. In the arrangement illustrated arms m^7 secured to the shaft m^3 carry a rod m^8 which is connected by a link m^9 80 to an arm m^{10} at the upper end of the shaft h^{14} which, as already described, is operatively connected with the shaft h^{16} and is moved therewith. The shoes m , when free to be moved from operative position, are drawn by 85 springs, as indicated at m^{11} in Figure 11, into inoperative position. By the movement of the actuator m^5 the shoes m , through contact of the actuator with the contact surfaces m^4 , are moved from inoperative to 90 operative position, the door being fully closed when this action takes place. As soon, however, as the movement of the door from closed position begins and before the contact surface m^4 at one side is free from the 95 actuator m^5 , the contact surface m^4 co-acts with a holding rail m^{12} which extends across the car nearly to the position occupied by the actuator m^5 , so that, during the continued 100 movement of the door and carriage k^4 , the shoes m are held in operative position.

Fixed to the shaft door b is a bracket b' on which is pivoted a bell crank lever b^2 , one arm, b^3 , of which is formed as a pawl to engage a short rack b^4 fixed to the hatchway 105 or front of the elevator shaft. Also pivoted on the bracket b' is a dog b^5 which cooperates with a pin b^6 carried by the bell crank lever b^2 . The unbalanced weight of the bell crank lever b^2 serves to hold the 110 pawl b^3 normally in engagement with the rack b^4 to lock the shaft door against movement from its closed position. The upper ends of the bell crank lever b^2 and the dog b^5 are enlarged to co-operate with the shoes 115 m . When, therefore, the car is stopped in position opposite a shaft door, the operator, by manipulation of the door controlling handle h^{17} , not only effects the release of the power storage device and the operative connection of the same with the car door, but at the same time causes the shoes m to swing 120 into operative position and thereby to disengage the latch b^3 and release the shaft door for movement with the car door through the 125 traveller k^4 .

For the purpose of cushioning the movement of the doors the traveller k^4 is provided with an arm k^8 which moves between two stops k^9 on a horizontal rod k^{10} which 130

- is provided at each end with a dashpot k^{11} . As the traveller moves in either direction its movement is free until the arm k^8 contacts with one or the other of the stops k^9 and thereafter the rod k^{10} moves with the traveller and therefore with the doors against the resistance of the corresponding dashpot, so that the doors are brought to rest gradually and quietly.
- 10 In order that the functioning of the several clutch controlling cams, when the door controller handle h^{17} is in neutral position, or in position for opening the door, or in position for closing the door, the several cams, in their relation to the roller h^7 of the corresponding lifter, are shown diagrammatically in Figures 12, 13 and 14. When the door controlling handle is in neutral position the holding cams h' and h^6 , which are alike in shape and in position on the shaft, stand with their low parts in line with the rollers h^7 , thereby permitting the clutches g' and g^6 to engage the holding rods e , e , so as to retain the weight in its relatively elevated position; at the same time the power storing cams h^2 and h^5 , also alike in shape and in position on the shaft, stand with their low points in line with the corresponding rollers h^7 , so that the power storing clutches g^2 and g^5 shall be in position to engage the parts c^4 and c^5 of the looped power storing cable, according to the direction of movement of the car; at the same time the door opening cam h^3 stands with its high point, at one side of its low point, in contact with the corresponding roller h^7 , thereby holding open the clutch g^3 and the door closing cam h^4 stands with its high point, at the other side of its low point, in contact with the corresponding roller h^7 , thereby holding open the door closing clutch. By the movement of the door controlling handle h^{17} in one direction to open the door or in the other direction to close the door, the several cams assume the positions shown in Figures 13 and 14 respectively. It will be noted that the angular extent of one-half of the low part of each cam and the angular extent of the rise of each cam are so proportioned (being substantially equal) that the closing clutch or the opening clutch, as the case may be, shall take hold of the corresponding member of the transmitting cable before the holding clutches let go, as otherwise the weight or power storing device would be released too soon. It will be noted further that whenever any clutch is free from the action of its corresponding cam, any downward movement of the weight and therefore of the clutch will tend, through the co-operation of the cam surface d^2 with the corresponding clutch roller g^9 , to cause the clutch roller to bind upon the corresponding rod or cable member as the case may be and also that both the power storing clutches will be opened automatically when the weight reaches its high point with respect to the car. It will also be noted that as any point in the standing part c^4 of the power storing cable has no movement in space, during the movement of the car, the power storing weight will be raised with respect to the car if it is coupled to the member c^4 during the downward movement of the car and that as any point in the intermediate portion c^5 of the power storing cable, between the guides c' and c^2 , has, during the upward movement of the car, an upward movement in space at a speed twice that of the car, the power storing weight, if coupled to the member c^5 of the cable during the upward movement of the car will be raised with respect to the car.
- 15 Reference has been made herein to the usual emergency release indicated at a^9 in Figure 1. In elevator practice this is provided in order that in an emergency, as in case of fire, the car can be moved notwithstanding the fact that the car door and the shaft doors are open. So long as the holding rail m^{12} is in operative position it would prevent the shoes m from being moved to inoperative position except when the door controlling handle is moved by the operator. It will therefore be understood that the holding rail m^{12} is not intended to be fixed permanently in position but is so supported that it may be moved out of position if conditions require, as by levers indicated at m^{12} .
- 20 It will be understood that various changes in details of construction and arrangement can be made to suit different conditions of use and that, except as pointed out in the accompanying claims, the invention is not limited to the particular construction shown and described herein nor to the joint co-action of all of the elements referred to herein.
- 25 I claim as my invention:
1. In an elevator, the combination of a car, a door, a power storage device mounted on the car, means whereby power is stored in said device through the movement of the car, means to hold said device against movement, and selective devices under the control of the operator whereby said device is connected operatively with the power storing means, the holding means and the door.
  2. In an elevator, the combination of a car, a door, a drum operatively connected with the door, a looped cable having its ends connected to the drum and wound thereon in opposite directions, a power storage device mounted on the car, and means under control of the operator to effect operative connection of the power storage device to either member of the looped cable.
  3. In an elevator, the combination of a car, a door, a power storage device mounted on the car and adapted to be connected operatively with the door, a power storage

cable having its ends fixed at the top and the bottom of the elevator shaft, guides on the car for the cable whereby an S-loop is formed in the cable, and means whereby operative connection is effected between one member of the S-loop and the power storage device during movement of the car in one direction and between another member of the S-loop and the power storage device and the movement of the car in the other direction.

4. In an elevator, the combination of a car, a door, a power storage device mounted on the car and operatively connected with the door, a power storage cable fixed at its upper and lower ends at the top and bottom of the elevator shaft, a clutch adapted to effect operative connection between the cable and the power storage device to store power in said device, and means under control of the operator to determine the opening or the closing of said clutch.

5. In an elevator, the combination of a car, a door, a power storage device mounted on the car and operatively connected with the door, a power storage cable fixed at its upper and lower ends at the top and bottom of the elevator shaft, a clutch adapted to effect operative connection between the cable and the power storage device to store power in said device, a cam in operative relation with said clutch to determine the opening or the closing thereof, and a controller handle and operative connections to shift the cam.

6. In an elevator, the combination of a car, a door, a power storage device mounted on the car and operatively connected with the door, a power storage cable fixed at its upper and lower ends at the top and bottom of the elevator shaft, a clutch adapted to effect operative connection between the cable and the power storage device to store power in said device, a cam in operative relation with the clutch to determine the opening or the closing thereof, a shaft on which said cam is mounted, a second shaft in operative relation with the first shaft, and a controller shaft in operative relation with said second shaft.

7. In an elevator, the combination of a car, a door, a power storage device mounted on the car and operatively connected with the door, a power storage cable fixed at its upper and lower ends at the top and bottom of the elevator shaft, a clutch adapted to effect operative connection between the cable and the power storage device to store power in said device, means under control of the operator to determine the opening or the closing of the clutch, and independent means to open the clutch automatically when power is fully stored in said device.

8. In an elevator, the combination of a car, a door, a power storage device mounted on the car and operatively connected with the door, a power storage cable fixed at its

upper and lower ends at the top and bottom of the elevator shaft, guides on the car whereby an S-loop is formed in the cable, clutches whereby operative connection is effected between two members of the S-loop of the cable and the power storage device, cams to control said clutches, and means under control of the operator to shift the cams.

9. In an elevator, the combination of a car, a door, a power storage device mounted on the car and operatively connected with the door, a power storage cable fixed at its upper and lower ends at the top and bottom of the elevator shaft, guides on the car whereby an S-loop is formed in the cable, clutches whereby operative connection is effected between two members of the S-loop of the cable and the power storage device, cams to control said clutches, means under control of the operator to shift the cams, and independent means to open the cams automatically when power is fully stored in said device.

10. In an elevator, the combination of a car, a door, a power storage device mounted on the car, a looped cable having its ends operatively connected with the door to effect movement thereof in opposite directions, clutches adapted to effect operative engagement between the two members of the looped cable and the power storage device, cams in operative relation with the clutches respectively to determine the opening or closing thereof, and means under the control of the operator to shift the cams.

11. In an elevator, the combination of a car, a door, a power storage device mounted on the car and operatively connected with the door, a holding rod mounted on the car, a clutch to effect connection between the holding rod and the power storage device to prevent movement of said device, and means under control of the operator to determine the opening or the closing of said clutch.

12. In an elevator, the combination of a car, a door, a power storage device mounted on the car and operatively connected with the door, a holding rod mounted on the car, a clutch to effect connection between the holding rod and the power storage device to prevent movement of said device, a cam in operative relation with the clutch to determine the opening or the closing thereof, and means under control of the operator to shift the cam.

13. In an elevator, the combination of a car, a door, a power storage device mounted on the car, a power storage cable fixed at its upper and lower ends at the top and bottom of the elevator shaft, a power transmitting cable operatively connected to the door, clutches to effect operative connection between the power storage cable and the

power storage device and between the power storage device and the transmitting cable, and means under the control of the operator to determine the opening and the closing of such clutches.

14. In an elevator, the combination of a car, a door, a power storage device mounted on the car, a power storage cable fixed at its upper and lower ends at the top and bottom of the elevator shaft, a power transmitting cable operatively connected to the door, clutches to effect operative connection between the power storage cable and the power storage device and between the power storage device and the transmitting cable, cams in operative relation with said clutches to determine the opening and the closing thereof, and means under the control of the operator to shift the cams.

15. In an elevator, the combination of a car, a door, a power storage device mounted on the car, a power storage cable fixed at its upper and lower ends at the top and bottom of the elevator shaft, a power transmitting cable operatively connected with the door, a holding rod mounted on the car, clutches to effect operative connection between the power storage cable and the power storage device, and the power storage device and the power transmitting cable and the power storage device and the holding rod and means under control of the operator to determine the opening or the closing of the clutches.

16. In an elevator, the combination of a car, a door, a power storage device mounted on the car, a power storage cable fixed at its upper and lower ends at the top and the bottom of the elevator shaft, a power transmitting cable operatively connected with the door, a holding rod mounted on the car, clutches to effect operative connection between the power storage cable and the power storage device, and the power storage device and the power transmitting cable and the power storage device and the holding rod, cams in operative relation with the clutches to determine the opening or the closing thereof, and means under the control of the operator to shift the cams.

17. In an elevator, the combination of a car, a door, a single weight mounted movably on the car, means to raise the weight with respect to the car, and means whereby the movement of the weight in its descent effects movement of the door in either direction at the will of the operator.

18. In an elevator, the combination of a car, a door, a single weight mounted movably on the car, a cable fixed at its upper and lower ends at the top and bottom of the elevator shaft, means to effect engagement between said cable and the weight during the movement of the car to raise the weight with respect to the car, and means whereby

movement of the weight in its descent effects movement of the door in either direction at the will of the operator.

19. In an elevator, the combination of a car, a door, a single weight mounted movably on the car, a cable fixed at its upper and lower ends at the top and bottom of the elevator shaft, guides on the car to form an S-loop in the cable, means to effect engagement between the weight and one member or another of the S-loop of the cable to raise the weight with respect to the car during movement of the car in either direction, and means whereby movement of the weight in its descent effects movement of the door in either direction at the will of the operator.

20. In an elevator, the combination of a car, a door, a single weight mounted movably on the car, means to raise the weight with respect to the car including a clutch, means under control of the operator to determine the opening or the closing of the clutch, and means whereby the movement of the weight in its descent effects movement of the door in either direction at the will of the operator.

21. In an elevator, the combination of a car, a door, a single weight mounted movably on the car, a cable fixed at its upper and lower ends at the top and bottom of the elevator shaft, a clutch to effect engagement between the cable and the weight to raise the weight with respect to the car, means under the control of the operator to determine the opening and the closing of the clutch, and means whereby the movement of the weight in its descent effects movement of the door in either direction at the will of the operator.

22. In an elevator, the combination of a car, a door, a single weight mounted movably on the car, a cable fixed at its upper and lower ends at the top and bottom of the elevator shaft, a clutch to effect engagement between the cable and the weight to raise the weight with respect to the car, a cam to determine the opening or the closing of the clutch, means under the control of the operator to shift the cam, and means whereby the movement of the weight in its descent effects movement of the door in either direction at the will of the operator.

23. In an elevator, the combination of a car, a door, a single weight mounted movably on the car, means to raise the weight with respect to the car, means to hold the weight in elevated position with respect to the car, means under control of the operator to release the weight, and means whereby the movement of the weight in its descent effects movement of the door in either direction at the will of the operator.

24. In an elevator, the combination of a car, a door, a single weight mounted movably on the car, means to raise the weight

with respect to the car, a holding rod mounted on the car, a clutch to effect engagement between the weight and the holding rod to hold the weight in elevated position, 5 means under control of the operator to determine the opening or the closing of the clutch, and means whereby the movement of the weight in its descent effects movement of the door in either direction at the will of 10 the operator.

25. In an elevator, the combination of a car, a door, a single weight mounted mov- 15 ably on the car, means to raise the weight with respect to the car, a holding rod mounted on the car, a clutch to effect engagement between the weight and the holding rod, a cam to determine the opening or the closing of the clutch, means under control of the operator to shift the clutch, and means 20 whereby the movement of the weight in its descent effects movement of the door in either direction at the will of the operator.

26. In an elevator, the combination of a car, a door, a single weight mounted mov- 25 ably on the car, means to raise the weight with respect to the car, a power transmission cable in operative connection with the door, a clutch to effect engagement between the weight and the cable, and means under con- 30 trol of the operator to determine the opening or the closing of the clutch.

27. In an elevator, the combination of a car, a door, a single weight mounted mov- 35 ably on the car, means to raise the weight with respect to the car, a power transmission cable in operative connection with the door, a clutch to effect engagement between the weight and the cable, a cam to determine the opening or the closing of the clutch, and 40 means under control of the operator to shift the cam.

28. In an elevator, the combination of a car, a door, a single weight mounted mov- 45 ably on the car, means to raise the weight with respect to the car, a looped cable having its ends operatively connected to the door to move the same in opposite direc- 50 tions, and means to effect operative connection between the weight and either member of the looped cable.

29. In an elevator, the combination of a car, a door, a single weight mounted mov- 55 ably on the car, means to raise the weight with respect to the car, a looped cable having its ends operatively connected to the door to move the same in opposite directions, clutches to effect engagement between the weight and the members of the looped cable, and means under the control of the operator to determine the opening or the closing of the 60 clutches.

30. In an elevator, the combination of a car, a door, a single weight mounted mov- 65 ably on the car, means to raise the weight

with respect to the car, a looped cable hav- 65 ing its ends operatively connected to the door to move the same in opposite directions, clutches to effect engagement between the weight and the members of the looped cable, 70 cams in operative relation with the clutches to determine the opening or the closing thereof, and means under the control of the operator to shift the cams.

31. In an elevator, the combination of a car, a door, a single weight mounted mov- 75 ably on the car, a cable fixed in the elevator shaft, a power transmitting cable operative- 80 ly connected with the door, clutches mounted on the weight to effect engagement between the weight and said cables respectively, and means under control of the operator to determine the opening or the closing of said clutches.

32. In an elevator, the combination of a car, a door, a single weight mounted mov- 85 ably on the car, a cable fixed in the elevator shaft, a power transmitting cable operative- 90 ly connected with the door, clutches mounted on the weight to effect engagement between the weight and said cables respectively, a cam shaft mounted on the weight, cams carried thereby in operative relation with the clutches respectively, and means under the control of the operator to shift the cam shaft.

33. In an elevator, the combination of a car, a door, a single weight mounted mov- 95 ably on the car, a cable fixed in the elevator shaft, a power transmitting cable operative- 100 ly connected with the door, clutches mounted on the weight, to effect engagement between the weight and said cables respectively, a cam shaft mounted on the weight, cams carried thereby in operative relation with the clutches respectively, a vertical shaft 105 mounted on the car, intermeshing gears on the cam shaft and the vertical shaft, the gear on the vertical shaft having a sliding engagement therewith, and means under control of the operator to oscillate the vertical shaft.

34. In an elevator, the combination of a car, a door, a single weight mounted mov- 115 ably on the car, a cable fixed in the elevator shaft, a power transmission cable carried by the car and operatively connected with the door, a holding rod, clutches carried by the weight and adapted to effect operative connection between the weight and the fixed cable, the transmission cable and the holding rod, and means to determine the opening or the closing of said clutches.

35. In an elevator, the combination of a car, a door, a single weight mounted mov- 120 ably on the car, means to raise the weight with respect to the car, means whereby the movement of the weight in its descent effects movement of the door in either direction, a

door controller handle to control said last named means, a car controller lever, and means whereby movement of the door controller handle from neutral position locks 5 the car controller against movement.

36. In an elevator, the combination of a car, a door, a single weight mounted movably on the car, means to raise the weight with respect to the car, means whereby 10 movement of the weight in its descent effects movement of the door, a car controller lever, and means whereby the operation of said last named means locks the car controller lever against movement.

37. In an elevator, the combination of a car, a car controller lever, a door, a door controlling shaft, a controller locking rod, a yoke having a pin and slot connection with the door controlling shaft, and an operative connection between said yoke and 20 the locking rod.

38. In an elevator, the combination of a car, a car controller lever, a door, a door controlling shaft, a controller locking rod, a 25 yoke having a pin and slot connection with the door controlling shaft, and a bell crank

lever connecting the yoke and the locking rod.

39. In an elevator, the combination of a car, a car controller lever, a door, a source 30 of power mounted on the car, a transmitting cable operatively connected with the source of power and with the door, a car controller locking rod, and means operated by the movement of the transmitting cable to shift 35 the locking rod to prevent movement of the car controller lever.

40. In an elevator, the combination of a car, a car controller lever, a door, a source of power mounted on the car, a transmitting 40 cable operatively connected with the source of power and with the door, a car controller locking rod, a screw shaft operated by movement of the transmitting cable, a travelling nut on said screw shaft, and means operated 45 by said travelling nut to shift the locking rod to prevent movement of the car controlling lever.

This specification signed this 18th day of November A. D. 1921.

CHRISTIAN G. LASSEN.
